SEWING TREE

Irma L. Gray, 1019 Elkgrove Ave., Apt. 1,
Venice, Calif. 90291

Filed Oct. 22, 1974, Ser. No. 516,980

Term of patent 14 years

Int. Cl. D6—99

U.S. Cl. D6—28

FIG. 1

FIG. 2

FIG. 3

FIG. 4

FIG. 1 is a front perspective view of a sewing tree showing my new design;

FIG. 2 is a top plan view thereof;

FIG. 3 is a side elevational view thereof; and,
FIG. 4 is a bottom plan view thereof.

I claim:

The ornamental design for a sewing tree, substantially as shown.
